CHAIR

Frederick G. Brixner, Kansas City, Mo.

Application April 16, 1934, Serial No. 720,735

8 Claims. (Cl. 240—4)

This invention relates to chairs and more particularly to a lounge type reading chair or davenport having built in lighting fixtures and has for its principal objects to project diffused light rays 5 at a desired angle upon the reading matter held by the occupant of the chair and in such a manner as to not reflect the light rays directly into his eyes.

Other important objects of the invention are to 10 provide a simplified chair construction having built in light features, to provide for air circulation through the light compartments to carry away heat of the lamps for promoting comfort of the occupant, and to provide for selectively 15 adjusting volume of the light rays to suit the needs of the chair's occupant.

In accomplishing these and other objects of the invention, as hereinafter described, I have provided details of structure, the preferred form 20 of which is illustrated in the accompanying drawing, wherein:

Fig. 1 is a perspective view of a lounge chair embodying the features of the present invention.

Fig. 2 is a longitudinal sectional view through 25 one of the built in light compartments on the line 2—2, Fig. 1.

Fig. 3 is a cross sectional view on the line 3—3, Fig. 2.

Fig. 4 is a horizontal section on the line 4—4, 30 Fig. 2.

Referring more in detail to the drawing:

1 designates a chair including side members 2 and 3 connected by suitable cross rails 4 for supporting a seat 5 and a back rest 6 inclined at a 35 convenient angle to the seat. The side members 2 and 3 are preferably of hollow construction and open at the bottom as at 7 for the circulation of air therethrough as hereinafter described. The side frames may also include built in book compartments 8 having shelves 9 for the convenience 40 of the occupant of the chair.

Built into the side frame members at the junction of the arm portions 10 with the back rest 6 are forwardly extending wings 11 and 12 having 45 light compartments for directing diffused rays of light downwardly and across the front of the occupant of the chair and onto the reading matter or other work held by the occupant.

By thus directing the light rays, the occupant 50 is provided with sufficient light and at the proper direction to relieve eye strain incidental to improperly directed light.

The wings 11 and 12 are best illustrated in Figs. 2, 3 and 4 wherein they are shown as including 55 a closed housing 13 having side walls 14 and 15

connected by a rear wall 16 inclined at the same angle as the back rest 6 and a vertically positioned front wall 17 having a curved portion 18 merging into the side wall 15.

The walls thus described are supported directly 5 upon the arm rest 10 to form an inner light compartment 19 which is closed at the top by a cover 20 having its rear portion 21 extending at right angles to the rear wall for mounting an electric light socket 22, later described.

The rounded front portions 18 are provided with rectangular openings 23 in which is mounted a frame 24 carrying translucent panels 25 conforming in curvature to the rounded portions. The panels 25 may be formed of glass, 15 frosted, or otherwise treated for diffusing light rays passing therethrough.

The inner face of the housings are lined with a layer of insulating material 26 which in turn is covered by a sheet metal liner 27 having 20 reflecting inner surfaces 28 except for that portion between the front edge 29 of the window openings and the side walls 14, which section 30 is painted or otherwise treated to prevent reflection of light rays which might be directed 25 into the eyes of the occupant of the chair.

Carried in the sockets 22 are light bulbs 31 which are connected in circuit with a plug-in connection 32 that is mounted on the back of the chair and to a switch 33 carried on the arm 30 of the frame member 2, as shown in Fig. 1.

The current for the circuit may be supplied from any convenient wall socket through a flexible cord having a plug adapted to be inserted in the plug connection 32.

In the illustrated instance, the light bulb of both fixtures are connected to a common switch; however, the lights may be individually connected with separate switches whereby the lights may be individually controlled without departing 40 from the spirit of the invention.

Due to the heat generated by the light bulbs, the light compartments become extremely hot and may offer discomfort to the occupant of the chair; however, I have provided means for circulating air through the light compartments to carry away the heat. This is accomplished by providing the front portion of each compartment with a tube 34 communicating with the interior of the side frames and extending upwardly 45 toward the front wall 17 as best shown in Fig. 2 whereby cool air admitted through the openings 7 passes through the tube 34 into the light compartments where it is directed by the front walls 17 toward the lamps 31. The air, upon 50

55

being heated by the lamps, is discharged through tubular vents 35 carried in the upper rear corners of the wings, as shown in Fig. 2.

In order to control the volume of the light admitted through the panels 25, the openings 23 are adapted to be covered by flexible doors 36 formed of colored celluloid or the like and which are slidable in guide tracks 37 provided between the end 17 and side walls 15 of the housing 10 and a covering material 38 forming a housing 39 for the door panels when they are in retracted position.

The frame 24 is preferably removable from the opening so as to permit access to the interior 15 of the light compartment for the removal and replacement of the light bulbs, when they become burned out.

In using the chair, the rays from the light bulbs are reflected by the lining 27 through the 20 translucent panel 25 directly onto the reading matter held by the occupant of the chair and the light rays move at a downwardly inclined angle in front of the body of the occupant so that if the occupant of the chair is wearing 25 glasses, the light rays will not be reflected by the lenses thereof into his eyes as is the case where the light rays are directed over his shoulder as in customary practice.

To control the volume and color of the light, 30 the door panels may be moved across the opening to cover selected portions of the panel, the doors being constructed of translucent colored material to pass only those rays of light which are non-injurious to the eyes.

35 During operation of the lamps, the interior of the compartments heat up, but the hot air will be displaced by thermosyphonic action through the ports 35 by the cold air passing from the bottom of the chair through the tube 34 to keep 40 up a constant circulation through the compartments.

From the foregoing, it is apparent that I have provided a chair with built in light features wherein the light rays are directed in a most 45 expeditious and efficient manner to promote comfort to the occupant by enhancing the visibility of the reading matter.

While I have particularly described my invention as applied to chairs, it is obvious that 50 the invention may be carried out in davenports and similar articles of furniture without departing from the spirit of the invention.

What I claim and desire to secure by Letters Patent is:

55 1. In combination with a chair including side, seat and back rest members, wing portions built into the juncture of the back rest with the side members and having openings located in front of an occupant seated in the chair, light sources supported in the wing portions for emitting light rays through the openings, means in the wing portions for circulating air around the light sources, and means covering the opening for diffusing the light passing through said openings.

60 2. In combination with a chair including side, seat and back rest members, a wing portion built into the juncture of the back rest with a side member and having an opening located in front of an occupant seated in the chair, a light

source supported in the wing portion for emitting light rays through the opening, an air inlet tube connected with the lower part of the wing portion, and an outlet tube connected with an upper part of the wing portion at a point adjacent the light source. 5

3. In combination with a chair including side, seat and back rest members, a wing portion built into the juncture of the back rest with the side members and having an opening located in front of an occupant seated in the chair, a reflector lining the wing portion, a translucent panel closing the opening, a light source supported in the wing portion for admitting light through the panel, and a shutter slidable across 15 the panel to regulate volume of light rays passing therethrough.

4. In combination with a chair including side, seat and back rest members, a wing portion built into the juncture of the back rest with the side 20 members and having a rounded front provided with an opening located in front of an occupant seated in the chair, a light source supported in the wing portion for emitting light rays through the opening, and means covering the opening for 25 diffusing the light passing through said opening.

5. In combination with a chair including side, seat and back rest members, a wing portion built into the juncture of the back rest with the side 30 members and having a rounded front provided with an opening located in front of an occupant seated in the chair, a light source supported in the wing portion for emitting light rays through the opening, means in the opening for diffusing the light rays, an air inlet tube connected with the lower part of the wing portion, and an outlet tube connected with an upper part of the wing portion at a point adjacent the light source. 35

6. In combination with a chair including side, seat and back rest members, a wing portion built into the juncture of the back rest with the side members and having an opening located in front of an occupant seated in the chair, a reflector lining the wing portion, an insulating material backing the reflector lining, a translucent panel closing the opening, a light source supported in the wing portion for admitting light through the panel, and a shutter slidable across the panel to regulate volume of light rays passing therethrough. 45 50

7. In combination with a chair including side, seat and back rest members, a wing portion built into the juncture of the back rest with the side members and having an opening located in front of an occupant seated in the chair, a light source supported in the wing portion to the rear of the occupant for emitting light rays through the opening, and means covering the opening for diffusing the light passing therethrough. 55 60

8. In combination with a chair including side, seat and back rest members, a wing portion built into the juncture of the back rest with the side members and having an opening located in front of the occupant seated in the chair, and a light source supported in the wing portion to the rear of the occupant for emitting light rays through the opening. 75

FREDERICK G. BRIXNER,
